Rinn Corporation, Elgin, Ill.

Filed Apr. 18, 1974, Ser. No. 461,952

Term of patent 14 years

Int. Cl. D24—01

U.S. Cl. D83—1 H

FIG. 1 is a perspective view of one side of an X-ray collimating extension tube positioning ring for anterior type dental X-ray film holders, showing my new design;

FIG. 2 is a plan view of the positioning ring side shown in FIG. 1;

FIG. 3 is a plan view of the positioning ring side opposite that shown in FIG. 2;

FIG. 4 is an edge view of the positioning ring taken substantially along line 4—4 of FIG. 2;

FIG. 5 is an edge elevational view of the positioning ring taken substantially along line 5—5 of FIG. 2;

FIG. 6 is a fragmental plan view taken substantially along line 6—6 of FIG. 1; and

FIG. 7 is a fragmental sectional view taken substantially along line 7—7 of FIG. 2.

I claim:

The ornamental design for an X-ray collimating extension tube positioning ring for anterior type dental X-ray film holders, substantially as shown.
